Primary Examiner — Cynthia Ramirez*Assistant Examiner* — Llorellys Martinez-Rivera(74) *Attorney, Agent, or Firm* — Roylance, Abrams, Berdo & Goodman, L.L.P.(57) **CLAIM**

The ornamental design for the duplex receptacle with night-light, as shown and described.

DESCRIPTION

FIG. 1 is a perspective view of a duplex receptacle with nightlight showing my new design;

FIG. 2 is a front view of the duplex receptacle with nightlight of FIG. 1;

FIG. 3 is a rear view of the duplex receptacle with nightlight of FIG. 1;

FIG. 4 is a left side view of the duplex receptacle with nightlight of FIG. 1;

FIG. 5 is a right side view of the duplex receptacle with nightlight of FIG. 1;

FIG. 6 is an end view of the duplex receptacle with nightlight taken from the right side of FIG. 4; and,

FIG. 7 is an end view of the duplex receptacle with nightlight taken from the left side of FIG. 4.
